US00D861679S

(12) **United States Design Patent** (10) Patent No.: **US D861,679 S**
(45) Date of Patent: ** Oct. 1, 2019

(54) **SET OF REMOVABLE BANDS FOR A BODY OF A WATCH**

(71) Applicant: **Fitbit, Inc.**, San Francisco, CA (US)

(72) Inventors: **Benjamin Patrick Robert Jean Riot**, San Francisco, CA (US); **Anthony Gerald Kern**, Pleasant Hill, CA (US); **Derek Jenchia Loh**, San Carlos, CA (US); **Bernhard Wildner**, San Francisco, CA (US); **Junyong Park**, San Francisco, CA (US); **Jeffrey Andrew Fisher**, Mountain View, CA (US); **Patrick James Markan**, San Francisco, CA (US); **Stephen Ronald Smilovitz**, Belmont, CA (US); **Yu Chuan Kang**, Taipei (TW)

(73) Assignee: **Fitbit, Inc.**, San Francisco, CA (US)

(**) Term: **15 Years**

(21) Appl. No.: **29/664,626**

(22) Filed: **Sep. 26, 2018**

CLAIM

The ornamental design for a set of removable bands for a body of a watch, as shown and described.

DESCRIPTION

FIG. 1 is a top, front, right side isometric view of a set of removable bands for a body of a watch showing our new design.

FIG. 2 is a right side elevation view of FIG. 1.

FIG. 3 is a left side elevation view of FIG. 1.

FIG. 4 front side elevation view of FIG. 1.

FIG. 5 is a back side elevation view of FIG. 1.

FIG. 6 is a top plan view of FIG. 1.

FIG. 7 is a bottom plan view of FIG. 1; and,

FIG. 8 is a bottom, left side isometric view of FIG. 1.

1 Claim, 8 Drawing Sheets
